ROTARY PUMP

Charles V. Copeland, Davenport, Iowa, and Frederick S. Schrage, Rock Island, Ill., assignors, by mesne assignments, to Joshua Hendy Iron Works, Sunnyville, Calif., a corporation of Nevada

Application November 3, 1940, Serial No. 364,900

8 Claims. (Cl. 103—96)

This invention relates to rotary pumps, and more particularly to pumps comprising a rotor having liquid impelling means, such as a plurality of marginal buckets operating in an annular pressure building passageway.

It is an object of the present invention to provide a pump which can be operated efficiently in either direction of rotation of the rotor.

It is another object of the present invention to provide a rotary pump which is relatively simple and easy to manufacture, and which is equally efficient when operated to pump in either direction.

It is a further object of the present invention to provide a pump wherein casing sections, including the inlet and outlet portions, are substantially identical and interchangeable.

Other objects will be apparent from the following description of the invention, as illustrated in the accompanying drawings, in which:

Figure 1 is an elevational view, partly in section, of a pump embodying the present invention;

Fig. 2 is a sectional view, with parts removed, taken on the line 2—2 of Fig. 1;

Fig. 3 is an elevational view of a portion of the rotor showing a desirable construction;

Fig. 4 is a plan view of one of the two identical casing members; and

Fig. 5 is an elevational view of one of the casing members showing the integral construction.

Referring more particularly to the drawings, wherein like parts are designated throughout the several views by like letters and numerals of reference, a pump casing has two substantially identical casing sections 1. Each casing section comprises a suitable supporting base portion 2, and a substantially cylindrical body portion. The body of each casing section is provided around its periphery with a rim 5 having a face 6 for cooperation with the corresponding face of the mating casing section, whereby a seal between the casing rims may be effected. Adjacent the rim of the casing section is an internal, annular channel 7, which registers with a corresponding annular channel in the other casing section and cooperates to form the pressure developing passageway of the pump.

Two casing sections, designated 1a and 1b in Figs. 1 and 2, may be secured together in fluid-tight relation by suitable means, such as bolts 8 which pass through mating apertures 8a of the rims. The bolt receiving apertures 8a are symmetrically arranged with respect to a plane parallel to the axis of the shaft and bisecting the

base 2, so that the apertures of each casing section will register with similar holes in the cooperating casing section when they are brought face to face. To facilitate machining of the rims, suitable recesses 9 may be formed in the faces 6 of the casing members. When the casing sections are thus secured together with the channels 7 in register, they form a pressure building passageway, the outer wall of which is formed by inner walls 10 of the rim portions 5 of the casing members.

Similarly, the inner portions of the channel 1 are formed by the shoulders of the central portions 11 concentric with the inner faces 10 of the rims. The central portions 11 are disposed sufficiently close to a rotor 17 to substantially restrict the flow of fluid radially inward from the fluid passageway formed by the channels 7.

The casing sections 1a and 1b may be provided with shaft supporting brackets or bosses 3, which are preferably internally threaded and substantially concentric with the annular pressure developing passageway. The bosses 3 receive suitable bearings 14 and 15, in which a rotor shaft 16, carrying the rotor 17, is rotatably supported. The bearings 14 and 15 may be adjusted by adjustable bearing nuts 12 and 13, which are externally threaded and engage the internal threads of one of the bosses 3.

The rotor is mounted on the rotor shaft 16 for rotation therewith, and comprises a circular disc 17 having a hub 19, an intermediate web portion and an outer peripheral portion carrying impeller ribs or vanes 20. The disc 17, near the base of the ribs 20, has a close working fit between the central portions 11 of the casing sections 1, whereby liquid in the annular passage is substantially prevented from flowing radially inward toward the central portion of the casing. The ribs 20 are preferably formed at both sides of the peripheral edge of the rotor and form suitable buckets which engage the liquid in the liquid passage. The edges of the buckets are spaced from the side walls of the liquid passageway and the peripheral edges of the buckets may be spaced from the circumferential wall of the passage 7.

Each casing section is provided with a port boss 4, and, as shown in Figs. 1 and 2, where two casing sections are assembled these bosses are designated as 4a and 4b. The bosses 4a and 4b form the inlet and outlet ports 22a and 22b, which are preferably internally threaded to receive suitable pipe connections (not shown) to bring the fluid to and take it away from the pump. Whether the port 22a be the inlet or outlet of

the pump is dependent upon the direction of rotation of the pump rotor. In Fig. 5, showing one of the casing sections, a port 22 is indicated in dotted lines at the upper right-hand portion, and this port communicates with one end of the liquid passageway 7.

When two casing sections are secured together, as shown in Figs. 1 and 2, the ports 22a and 22b are disposed angularly relative to each other, each port being opposite the end of the passageway 7 in the other casing section. Between the ports 22a and 22b the casing sections are shaped to provide a stop 25 to prevent the fluid being pumped from passing directly from the outlet end of the passageway 7 to the inlet end thereof. To provide the stop, each pump casing section has a shoulder 26 extending radially inwardly from the rim, and this portion 26 closely overlies the peripheral edge of the rotor. Also, each casing section is provided with a stop portion 21 extending closely adjacent the sides of the rotor in the region of the stop so that liquid being pumped will be deflected from the liquid passageway directly from the outlet of the pump.

Adjacent one end of the passageway 7 in each of the casing members is a depressed portion. In the casing member 1a the depressed portion 24a (Fig. 2) is opposite the port 22b of the other casing section, and in the casing section 1b the depressed portion 24b is opposite the port 22a of the first mentioned casing section. These depressed portions facilitate ingress of the water to both sides of the rapidly moving rotor on one side of the stop and egress of the water from both sides of the rotor on the other side of the stop, the registering stops of each section cooperating to prevent leakage of water therebetween. It will thus be seen that in each casing member one end of the channel 7 terminates in a port 22, the other end terminates in a large depressed portion to cooperate with the port of another casing section.

Leakage of fluid from the central portion of the casing through the shaft openings is prevented by suitable packing glands, such as seals 28. Each seal comprises a rotatable deformable member 29 of rubberlike material and a rotatable sealing member 30, which may be a metal or a self-lubricating metallic material, and which is pressed against the surface of a stationary metal sealing member 31 by a spring 32. A stationary deformable ring 33 of rubberlike material is disposed between the stationary sealing member and a shoulder 34 and is adapted to be forced against the surface of the sealing shoulder 24 by the spring 32 so as to effect a fluid seal between the stationary, wear-resistant member 31 and the shoulder 34. The rotatable deformable member 29 effects a seal between the shaft and the rotatable member 30. A centrifugal deflector 36, which is provided on the rotor shaft between the pump and the bearing to deflect and throw off by centrifugal force any liquid that may collect on the rotor shaft, thereby prevents such liquid from entering the bearings.

The pump may be driven by any prime mover, such as an electric motor coupled to the shaft 16. When the pump is in operation with the rotor turning clockwise (from the shaft coupled end) 22b is the inlet and 22a is the outlet. The movement of the rotor with the buckets in its marginal portion through the passageway 7 causes the liquid to move from the inlet 22b through the pressure developing passage and be discharged through the outlet 22a at relatively high pressure.

Similarly, when the rotor is operated in a counterclockwise direction the outlet is 22b and the inlet is 22a. Thus, with the above construction, the pump will have the same performance characteristics, regardless of the direction in which the rotor is caused to rotate.

It will be seen from Fig. 5 that the stop portion of the pump section and the major portion of the pressure developing passage are symmetrically disposed with respect to a plane bisecting the stop and passing through the axis of the casing. The ends of the pressure developing passage in a single casing section are different in that one end opens to a port and the other does not. If the casing section be made with an integral base, the base is also bisected by and symmetrically disposed with respect to the above mentioned plane. When the two pump casing sections are disposed together, it will be seen that the inlet and outlet ports are equidistant from the axial plane bisecting the stop. It is also apparent from the drawing that the major portion of the pressure developing passage, as well as of the pump casing, is symmetrically disposed about an axial plane symmetrically dividing the rotor.

Pumps of the type having a rotor with marginal buckets to engage liquid and cause it to pass through an annular pressure developing passageway may be made relatively simply and at considerable saving in cost by utilizing the present invention and making the casing sections identical, with portions symmetrical or equidistant from an axial plane, as set forth above.

It will be understood that numerous modifications of the construction shown may be resorted to without departing from the spirit of this invention, as defined in the appended claims.

What we claim is:

1. A pump casing for a pressure developing pump of the type having a rotor with a central disc portion and with a plurality of marginal buckets to develop fluid pressure in an annular pressure developing passageway, comprising two substantially identical mating casing sections, each section having an integral base portion, an integral shaft supporting boss and a substantially cylindrical body portion, said body portion having a central portion for close working fit with said disc portion of said rotor to prevent liquid from flowing inwardly toward the central portion of said casing section and a rim which has a face for cooperation with the face of the mating sections, an annular channel in each section adjacent said rim, the channels in the two sections registering and forming together an annular pressure developing fluid passageway, the terminals of said fluid passageway being ports for ingress or egress of fluid, a stop between said ports for deflecting fluid from said passageway into the outlet port, said stop comprising a shoulder portion in each section adapted to closely overlie the outer periphery of said rotor and extending to the plane of the face of said rim, said ports and portions of said passageway being substantially equidistant from an axial plane bisecting said stop and said base portion, portions of said passageway and said stop being symmetrical with respect to said plane, whereby a pump is provided in which the rotor may be caused to rotate in either direction without varying the characteristics of the pump.

2. A pump casing for a pressure developing pump of the type having a rotor with a central disc portion and with a plurality of marginal

buckets to develop fluid pressure in an annular pressure developing passageway, comprising two substantially identical mating casing sections, each section having a substantially cylindrical body portion, said body portion having a central portion for close working fit with said disc portion of said rotor to prevent liquid from flowing inwardly toward the central portion of said casing section and a rim which has a face for cooperation with the face of the mating sections, an annular channel in each section adjacent said rim, the channels in the two sections registering and forming together an annular pressure developing fluid passageway, the terminals of said fluid passageway being ports for ingress or egress of fluid, a stop between said ports for deflecting fluid from said passageway into the outlet port, said stop comprising shoulder portions adapted to closely overlie the outer periphery of said rotor and extending to the plane of the face of said rim, said ports and portions of said passageway being substantially equidistant from an axial plane bisecting said stop, portions of said passageway and said stop being symmetrical with respect to said plane, whereby a pump is provided in which the rotor may be caused to rotate in either direction without varying the characteristics of the pump.

3. A pump casing for a pressure developing pump of the type having a rotor with a central disc portion, and with a plurality of marginal buckets to develop fluid pressure in an annular pressure developing passageway, comprising two substantially identical mating casing sections, each section having an integral base portion, an integral shaft supporting boss concentric with said pressure developing passageway and a substantially cylindrical body portion, said body portion having a central portion for close working fit with said disc portion of said rotor to prevent liquid from flowing inwardly toward the central portion of said casing section and a rim which has a face for cooperation with the face of the mating sections, an annular channel in each section adjacent said rim, the channels in the two sections registering and forming together an annular pressure developing fluid passageway, the terminals of said fluid passageway being ports for ingress or egress of fluid, a stop between said ports for deflecting fluid from said passageway into the outlet port, said ports and portions of said passageway being substantially equidistant from an axial plane bisecting said stop and said base portion, portions of said pressure developing passageway intermediate its ends and portions of said stop being symmetrical with respect to said plane, whereby a pump is provided in which the rotor may be caused to rotate in either direction without varying the characteristics of the pump.

4. A pump casing for a pressure developing pump of the type having a rotor with a central disc portion and with a plurality of marginal buckets to develop fluid pressure in an annular pressure developing passageway, comprising two substantially identical mating casing sections, each section having a substantially cylindrical body portion and an integral base, said body portion having a central portion for close working fit with said disc portion of said rotor to prevent liquid from flowing inwardly toward the central portion of said casing section and a rim which has a face for cooperation with the face of the mating sections, an annular channel in each section adjacent said rim, the channels in the two

sections registering and forming together an annular pressure developing fluid passageway, the terminals of said fluid passageway being ports for ingress or egress of fluid, a stop comprising a shoulder portion in each casing section between said ports for deflecting fluid from said passageway into the outlet port, said ports and portions of said passageway being substantially equidistant from an axial plane bisecting said stop, portions of said passageway intermediate its ends and portions of said stop being symmetrical with respect to said plane, whereby a pump is provided in which the rotor may be caused to rotate in either direction without varying the characteristics of the pump.

5. A pump casing for a pressure developing pump of the type having a rotor with a central disc portion and with a plurality of marginal buckets to develop fluid pressure in an annular pressure developing passageway, comprising two substantially identical mating sections, each mating section having a base portion, a hub portion to receive a rotor shaft and a fluid seal, and a body portion to receive a rotor disc, said body portion having a central portion for close working fit with said disc portion of said rotor to prevent liquid from flowing inwardly toward the central portion of said casing section and a rim which has a face for cooperation with a corresponding face of the mating sections, an annular pressure developing channel in each section adjacent said rim and having a port at one end, the channels in the two sections registering and forming a pressure developing passageway with each end terminating in a fluid port and a stop between the terminals of said passageway, said stop having a shoulder which closely overlies the periphery of said rotor disc and a portion closely adjacent the sides of said disc, said ports being equidistant from a vertical, axial plane substantially symmetrically dividing said base and said stop, portions of said pressure developing passageway intermediate its ends and portions of said stop being symmetrical with respect to said plane.

6. A single stage pump having a rotor with a central disc portion and with a plurality of marginal buckets to develop fluid pressure in an annular pressure developing passageway, two substantially identical mating casing sections, each casing section having a portion in close working fit with a side of the rotor radially inwardly of said passageway to prevent flow of liquid radially inwardly toward the central portion of the pump, each section having a substantially cylindrical body portion and an integral shaft supporting boss, said boss being internally threaded and carrying bearings adjustable longitudinally of said boss to center said rotor with respect to said sections, said cylindrical body portion having a central portion and a rim with a face for cooperation with the corresponding face of the mating section, an annular channel adjacent the rim, said channel terminating at one end in a port and at the other end in a depressed portion, a shoulder for closely overlying the peripheral edge of the rotor disposed between the terminals of said channel, said shoulder terminating substantially at the plane of the face of said rim, portions of said shoulder and said channel intermediate its ends being substantially symmetrically arranged about an axial plane bisecting said shoulder, whereby a pump is provided in which the rotor may be caused to rotate in either direc-

tion without varying the characteristics of the pump.

7. A single stage pump having a rotor with a central disc portion and with a plurality of marginal buckets to develop fluid pressure in an annular pressure developing passageway, two substantially identical mating casing sections, each casing section having a portion in close working fit with a side of the rotor radially inwardly of said passageway to prevent flow of liquid radially inwardly toward the central portion of the pump, each section having a substantially cylindrical body portion and an integral shaft supporting boss carrying adjustable bearings to center said rotor in said casing, said body portions having a central portion and a rim with a face for cooperation with the corresponding face of the mating section, an annular channel adjacent the rim, said channel terminating at one end in a port and at the other end in a depressed portion, a shoulder for closely overlying the peripheral edge of the rotor disposed between the terminals of said channel, said shoulder terminating substantially at the plane of the face of said rim, said channel intermediate its ends being substantially symmetrically arranged about an axial plane bisecting said shoulder, whereby a pump is provided in which the rotor may be caused to rotate in either direction without varying the characteristics of the pump.

8. In a rotary pressure developing pump a cas-

ing, a pressure developing passage in said casing, a rotor having buckets to engage liquid in said passage, said casing comprising a pair of substantially identical casing sections cooperatively providing said liquid pressure developing passage, an inlet and an outlet communicating with the ends of said passage, a liquid deflecting stop having a portion which closely overlies the peripheral edges of the rotor and a portion which closely overlies the sides of said rotor in the vicinity of the marginal buckets, said stop being between the inlet and outlet to direct fluid into the outlet, portions of said pressure developing passage and portions of said stop on each side of a medial plane through said stop and through the axis of the pump being substantially identical, said pressure developing passage at the lateral edges of said buckets being of substantially greater width than the width of the opening in said stop, said inlet and said outlet being substantially equidistant from said plane whereby a pump is provided in which the rotor may be caused to rotate in either direction without changing the characteristics of the pump, said rotor having a solid annular portion in working fit within said casing radially inwardly of said pressure developing passage which prevents liquid from flowing radially inward toward the central portion of said casing.
